UNITED STATES PATENT OFFICE

RAYMOND B. PRICE, OF NEW YORK, N. Y., ASSIGNOR, BY MESNE ASSIGNMENTS, TO THE GOODYEAR'S METALLIC RUBBER SHOE COMPANY, OF NAUGATUCK, CONNECTICUT, A CORPORATION OF CONNECTICUT.

RUBBER FOOTWEAR.

1,309,047.

Specification of Letters Patent.

Patented July 8, 1919.

Original application filed December 30, 1911, Serial No. 668,791. Divided and this application filed October 22, 1914. Serial No. 867,950.

To all whom it may concern:

Be it known that I, RAYMOND B. PRICE, a citizen of the United States, residing at New York, county and State of New York, have invented new and Improved Rubber Footwear, of which the following is a full, clear, and exact description.

The present invention relates to a new and improved article of foot-wear composed of rubber and fabric disclosed in my prior application filed December 30, 1911, Serial No. 668,791, of which the present application is a division. The object of this invention is to provide a rubber boot or shoe of any style in which the various layers of fabric and rubber are united more firmly and durably than has heretofore been possible with the same materials and in which the adhesion of the various layers to each other is of the same degree of strength throughout the entire surface. The invention also provides a boot or shoe in which the interior surface is perfectly smooth along the abutting edges of the various portions of the lining and variations in the thickness of the wall of the boot or shoe appear in marked degree on the outside and not at all on the inside. This latter feature (as well as the former) gives to the boot or shoe a much better wearing quality in that there are no projections on the inside of the boot which afford initial means of engagement with the foot of the wearer, or in the case of an overshoe with the ordinary leather shoe.

35 The article of rubber foot-wear disclosed in my said prior application Serial No. 668,791, and which is the subject of this application for patent is produced by the process set forth in my said prior application.

40 To explain more fully the difference between the boot which is the subject of my invention and this application for patent compared with the prior art, it is desirable to refer to the ordinary process of manufacturing boots and shoes as practised before the invention which is the subject of my aforesaid application for Letters Patent. The ordinary process was as follows: The various rubber elements going to make up a shoe were sheeted out to proper thickness and then cut to proper size and shape. The

fabric or strength-giving element of the boot or shoe was first coated with rubber in a calender or by spreading (both processes well known in the art), and then the fabric with the coating of rubber was cut to the desired size and shape. A suitable last was then taken and the various elements applied to the last or form in proper position and sequence and the adhesion of the various portions of the boot or shoe was secured by pressure applied by the manipulation of a hand-roller by a skilled workman. After the final formation of the boot or shoe on the last, the last carrying the boot or shoe, was placed in a suitable heater and vulcanized. The union of the various portions of a boot or shoe so built up depends upon the time and care and skill of the workman in the rolling down process. If the roller could be used with the application of the proper amount of pressure and uniformly throughout the entire surface the maximum efficiency in wearing quality would be obtained, provided of course the quality of the materials used is appropriate and the vulcanizing process is correct. But no matter how skillfully the boot or shoe may be made by such a process it is impossible to obtain uniform adhesion throughout the entire area of the article. This is easily demonstrated by taking a boot or shoe so made and separating the various plies. If the lining of a rubber boot be stripped from the adjacent layer of rubber the marks of the roller will be plainly seen on the surface of the fabric lining and the opposed surface of the rubber, and where the pressure of the roller has been exerted a marked difference is apparent from where very little or no pressure has been exerted, and moreover, the fabric plies strip from each other with varying or unequal resistance.

45 In a boot or shoe made according to my invention on the other hand, the process of manufacture may be the same as is common in the art up to the point of building or associating the various elements of fabric and rubber on the last to give the desired formation; and even this portion of the process may be the same. By this I mean 95 that the workman may associate the various

portions of fabric on the last and rub them into contact with his rolling tool just as in the old method, but this rolling or pressing action is not essential. Instead of this latter action, the various elements of fabric and rubber may be simply laid in position on the last and no rolling applied to effect adhesion of the various layers, although in practice a slight application of the rolling process is given. After the boot or shoe is built on the last or form, it is vulcanized in a peculiar manner, which is fully set forth in detail in my said application, the essential feature of which is that a fluid pressure is applied to the outer surface of the boot or shoe while supported on the last, and this pressure is permitted to effect its maximum efficiency by establishing a communication upon the inside of the article, either through the last or otherwise, with a fluid pressure lower than that exerted on the outer surface. The usual and ordinary practice is to make the last or form with perforations and communicate such perforations with a vacuum producing apparatus so that there is exerted on the inner surface of the article a sucking action, and on the outside a pressure. In a boot or shoe so made the various layers of rubber and fabric adhere to each other with much greater tenacity than is the case with a boot or shoe made by the old process, and moreover, no matter how the boot or shoe may have been built up, whether by simply laying the various elements in position or by rolling down after they have been laid in position, an important factor producing the adhesion or union of the various layers is the pressure applied to the outside of the article operating against a lower pressure, or a vacuum, on the inside of the article. No matter how the boot or shoe may have been built, after it has been vulcanized in this manner the adhesion of the various elements is of greatly improved strength, and is uniform throughout every portion of the area. Upon stripping the various layers of such a boot practically no rolling marks are visible, but on the other hand the appearance is substantially uniform throughout every portion of the surface. Additionally, the inner surface of the boot or shoe when made on a smooth last (as is the universal practice) is correspondingly smooth; and lapping or abutting joints do not affect this smooth character of the inside surface. On the other hand, the laps and inequalities of thickness of the wall of the boot or shoe appear on the outside of the article with well defined clearness. In a boot or shoe so made and characterized by the uniform adhesion of the various layers, which means that the adhesion is of maximum efficiency, as distinguished from a boot or shoe having various degrees of adhesive qualities in various portions of its wall as

formerly made, even when using the same fabric and rubber and the correct vulcanization process, the result is far superior and in practice it has been found to have very much improved wearing qualities over the old boot or shoe.

In the drawings I have illustrated the invention, as embodied in a rubber boot, in which drawings—

Figure 1 is a perspective view;

Fig. 2 is a longitudinal section of the foot portion of a boot made according to old methods;

Fig. 3 is a similar view of the foot portion of a boot embodying my invention;

Fig. 4 is a view of a portion of the leg of a boot showing the outer layer of rubber partially stripped from the supporting layer of fabric and illustrating the appearance of the parts in a boot made according to old methods, while

Fig. 5 is a similar view illustrating the appearance of the same parts in a boot embodying my invention;

Fig. 6 is a sectional view along line 6—6 of Fig. 2;

Fig. 7 is a sectional view along line 7—7 of Fig. 3;

Fig. 8 is a sectional view taken along line 8—8 of Fig. 2; and

Fig. 9 is a sectional view taken along line 9—9 of Fig. 3.

Referring to the drawings in detail, A designates the boot comprising the foot portion *a* and the leg portion *a'*. In Fig. 1 I have illustrated how the boot subject of the present invention bears on the outside well defined marks delineating the various separate elements from which it is made up. These demarking lines are indicated by the letter *a*'.

In Figs. 4 and 5 the outer layer of rubber *B* is shown partially stripped away and folded back from its supporting fabric *B'*. In the process of manufacture the fabric *B'* is usually coated with a layer of rubber either by frictioning the rubber into the meshes of the fabric by a calender or by spreading a rubber solution, both processes being well known. After the various layers of such fabric as well as the various other layers of different materials have been placed in appropriate position the outer layer of rubber is placed in position and the entire wall structure given a compacting operation by the workman applying pressure thereto through the medium of a hand roller. It is practically impossible to give a uniform compacting effect in this way no matter how careful the workman may be; and after vulcanization in the old way this inequality is emphasized in and made apparent by the haphazard unequal degrees of tenacity with which the various plies adhere in the different portions of their surfaces as well as by

the fact that in a boot or shoe made according to the old processes the adherence of opposed layers, even where the greatest hand pressure has been properly applied, is inferior to the degree of adherence of the layers in a boot made according to the present invention. In Fig. 4 there is illustrated the general appearance presented on stripping the outer layer of rubber from the supporting layer of fabric in a boot made according to old methods. In this view the darker shaded portions *b* indicate and fairly represent the surface appearance where the hand roller has been applied in the building operation, while in the intervening spaces the hand roller either has not been applied at all, or ineffectually. If a strip of the outer layer of rubber be torn away from the supporting fabric in a direction at right angles 20 to the length of the cuff of the boot, and therefore at right angles to the direction of application of the hand roller, the strip will give varying resistances. Where the hand roller has been effectually applied (as at the 25 portions marked *b*) the adhesion will be very good, but the intervening spaces marked *b'* will resist the stripping action very little, or at any rate, to a greatly diminished degree. In Fig. 5 I have attempted to illustrate the 30 appearance of the inner surfaces after stripping away the outer layer of rubber from a boot embodying my invention. In this case there is practically no variation in appearance in the different portions, and substantially no variation in actual adherence; 35 but on the other hand a uniform appearance and a very much improved and substantially uniform adhesion.

Again in Fig. 6 I have illustrated a lining 40 joint in a boot made by the old method, in which, it will be seen that the double thickness of the fabric *C* at the joint makes an ugly irregularity on the inside affording a ready point of engagement from which to 45 initiate separation of the fabric lining from the rubber and thereby shortening the useful wearing life of the boot, while in Fig. 7, illustrating the lining joint in a boot embodying the present invention, the joint is 50 perfectly smooth on the inside and the irregularity of surface is transferred to the outer surface.

In Figs. 8 and 9 there is illustrated the difference between a boot embodying my invention and a boot made according to old methods particularly as regards the relationship between the insole and the side wall of the foot portion of the boot. In the latter case the edge of the insole *D* projects in a 55 decided manner while in a boot embodying my invention (Fig. 9) the insole and the side wall of the boot come into intimate contact, the surface of one smoothly continuing the surface of the other without break 60 or surface inequality.

In a word, then, the boot or shoe subject of this application has its walls compacted uniformly throughout so that the various plies adhere to each other with substantially equal tenacity in every portion, the inner 70 surface being perfectly smooth and devoid of irregularities or projections resulting from overlapping of plies or differences in the thickness of the wall structure at various points, while these laps and variations in 75 wall thickness appear in well defined manner on the outside. From this it results that the boot or shoe is equally strong, compact and solid throughout and has no structurally vulnerable portions as compared with other 80 portions, so that its life of usefulness is measured by the inherent strength and wear-resisting quality of the article as a whole and not hastened by the breaking down of a weak point resulting from a structural 85 defect, as shown for instance in Figs. 2 and 8 at the thickened portions indicated by *b*, which may be moisture, dirt and the like to set up chemical processes acting to hasten deterioration, or, on the other hand, affording undesirable points of engagement from which mechanical disruption of the structure is inevitable.

While I have said that in the boot subject of the present invention the adhesion of 95 the plies is uniform and the same throughout the entire surface, I do not by this mean that there is absolutely no difference in the degree of adhesion of any given plies at points widely separated, but I do mean that 100 if there is a difference, it develops through regular and infinitesimal graduations and is, in any event, only slight. However, it is true that along any given horizontal plane the adhesion of the plies is of substantially 105 the same tenacity, understanding, of course, that the materials are the same; so that when I define the invention in the claims as characterized by the fact that the adhesion between opposed layers along a horizontal 110 plane is of the same tenacity, I mean that it is substantially the same where the materials of the plies are the same. If the materials of the plies at one point of a horizontal plane vary from the materials at another 115 point in the same horizontal plane the tenacity of adhesion of one as compared with the other may differ, but in such a case there will be practically no variation in adhesion along a horizontal plane throughout 120 the continuity of identical materials.

What is claimed as new is:

1. A vulcanized rubber boot or shoe composed of rubber and unwrinkled fabric in which the adhesion between opposed layers 125 along a horizontal plane is of the same tenacity.
2. A vulcanized rubber boot or shoe composed of layers of vulcanized rubber and fibrous materials in which a layer of rubber 130

is vulcanized in intimate and continuous contact with its adjacent layer throughout its superficial area.

3. A vulcanized rubber boot or shoe composed of layers of vulcanized rubber and fibrous materials in which a layer of rubber is vulcanized in intimate and continuous contact with its adjacent layer throughout its entire superficial area, the adhesion between opposed layers along a horizontal plane being of the same tenacity.

4. A vulcanized rubber boot or shoe composed of layers of vulcanized rubber and fabric in which a layer of rubber is vulcanized in intimate and continuous contact with its adjacent layers throughout its entire superficial area, the inner surface of the boot or shoe being smooth.

5. A vulcanized rubber boot or shoe com-

posed of layers of vulcanized rubber and fabric in which a layer of rubber is vulcanized in intimate and continuous contact with an adjacent layer of fabric throughout its superficial area.

6. A vulcanized rubber boot or shoe composed of layers of vulcanized rubber and fabric in which a layer of rubber is vulcanized in intimate and continuous contact with an adjacent layer of fabric throughout its superficial area and extends into the interstices of the fabric to the same extent along a horizontal plane.

Signed this 16th day of October, 1914, at the city, county, and State of New York.

RAYMOND B. PRICE.
